UNITED STATES PATENT OFFICE.

WILLIAM T. HORMES, OF GOVANS, MARYLAND, ASSIGNOR TO SOLOMON HIMMEL, OF BALTIMORE, MARYLAND.

DISPLAY-CABINET.

1,176,713.

Specification of Letters Patent. Patented Mar. 21, 1916.

Application filed January 15, 1915. Serial No. 2,450.

To all whom it may concern:

Be it known that I, WILLIAM T. HORMES, a citizen of the United States, residing at Govans, in the county of Baltimore and 5 State of Maryland, have invented new and useful Improvements in Display-Cabinets, of which the following is a specification.

This invention is a display cabinet of the type composed of a plurality of sectional units.

One of the objects of the invention is to produce a sectional cabinet for use in stores, warerooms, and the like, in which the arrangement and style of the respective units 10 may be changed or altered at will to suit different conditions that may be imposed by various merchants, and to conform to architectural conditions.

A further object is to provide knock-down units of sectional construction, which 20 may be superposed one upon the other, to form a stack of units.

A further object is to provide improved means coöperating with the units of each 25 stack, to stiffen the stack and to prevent relative displacement of the parts.

A further object is to provide improved means for so connecting contiguous or adjoining stacks that relative movement of the 30 stacks is prevented and the entire structure made rigid.

A further object is to provide means whereby the units and stacks may be compactly assembled to take up a minimum 35 space, and to have the appearance of a single unitary structure.

The invention will be hereinafter fully set forth and particularly pointed out in the claims.

40 In the accompanying drawing:—Figure 1 is a perspective view illustrating a display cabinet constructed in accordance with my invention. Fig. 2 is a horizontal sectional view. Fig. 3 is a vertical sectional view on the line 3—3, Fig. 2. Fig. 4 is a detail perspective view of the end portion of a unit, with the pilaster removed.

Referring to the drawing, three separate and distinct stacks 10, 11 and 12 are illustrated, each stack being formed of a plurality of superposed units. Each unit comprises a base member, 13, a top member 14, and end members 15 and 16, respectively, the end members being somewhat narrower than 55 the top and bottom members. The forward

edges of the top and bottom members are cut away near each end, as indicated at 17, to accommodate the pilasters 18. The top and bottom members are removably connected to the end members by means of hook 60 and socket elements, the top edge of each end member being provided with a slotted plate 19, the slot 20 of which coincides with a recess 21 formed in said end edge. The underface of the top member is provided at 65 the ends of said member, with plates 22 provided with hooks 23 arranged to pass through the slots 20 of the plates 19 into the recesses 21, a slight rearward movement of the top member causing the hooks 23 to pass 70 beneath the plates 19, thus locking the top member and the end members together. The bottom edges of said end members are also provided with similar slotted plates and recessed portions, indicated at 24, to receive 75 complementary hooks 25 secured to the top face of the bottom member. By means of this arrangement the unit is made up of knock-down sections which may be readily assembled or separated, as may be desired. 80 If desired, the unit may be provided with shelves 25 provided with hook members 26 on their ends to engage complementary slotted plates and recesses 27 with which the inner faces of the end members are provided. 85 The front edges of the end members are provided with slotted plates and corresponding recesses 28, to receive complementary hooks 29 carried by the pilasters 18.

It will be understood that the end members 15 and 16 may be of varying lengths to provide a unit of any desired height, in which event sectional units each including bottom and top members 13' and 14', respectively, may be utilized as shown in Fig. 90 1. If a stack of units is desired, the same may be built up of a plurality of sections such as illustrated in Figs. 3 and 4, each section being constructed of top, bottom and end members, as above described, and a plurality of said sections, are placed one upon the other, until the desired number have 95 been assembled. The hooks 29 of a pilaster are then made to engage the plates and recess 28, and a downward push upon the pilaster causes the same to be interlocked 100 with all of the superposed units. In this manner the pilaster stiffens the stack and retains all of the units in proper relation. By providing the cut-away portions 17 the pi- 110

laster is made to form an abutment to prevent forward or unlocking movement of the top and bottom members, and by making the shelves 25 of the same width as the end 5 members, the pilasters will also prevent forward movement of said shelves, thereby locking them in position. When it is desired to employ more than one stack, the end members of the units forming the respective 10 stacks are abutted, one against the other, and the pilaster made of sufficient width to cover the abutting end members. The hooks 29 are then arranged in pairs, one hook of each pair engaging the end member of one stack, the other hook of each pair engaging the abutting end member of the other stack. In this manner the adjoining stacks are rigidly and securely locked together, and relative movement thereof prevented. It is preferable 20 to place the ends of the stacks one against the other, to economize floor space, but if for any reason it should be desired to slightly separate the ends of the stacks, it is only necessary to correspondingly increase 25 the width of the pilaster, and separate the hooks of each pair to conform thereto.

It is obvious that the character of the respective units may be varied at will, various types of such units being illustrated in the 30 drawing. For instance, the stack 10 is shown as composed of a unit having drawers 30, units 31 provided with display openings in the fronts thereof, and a unit 32 in the form of a compartment closed by glass 35 doors. The stack 11 comprises a section 33 provided with open shelves, a unit 34 divided into compartments, and a unit 35 in the form of a large glass inclosed compartment. The stack 12 is formed of a section 40 36 provided with drawers, sections 37 provided with smaller drawers, and a glass inclosed unit 38. The end panels 39 are secured to the adjacent end members of the respective units in suitable manner, as by 45 means of screws 40, the end pilaster extending over the front edge of the panel and the corresponding edges of end members of the units.

Having thus explained the nature of my 50 invention and described an operative manner of constructing and using the same, although without attempting to set forth all of the forms in which it may be made, or all of the forms of its use, what I claim is:—

55 1. A display cabinet of the character described comprising end, top and bottom members having locking devices, the locking devices of the end members being complementary to those of the other members, said 60 locking devices being engaged and disengaged by movement of the top and bottom members relative to said end members, pilaster members, said end members and said pilaster members also having complementary locking devices engaged and disengaged by

movement of said pilaster members relative to said end members, the movement of the pilaster members being at an angle to the movement of the top and bottom members, whereby engagement of the pilaster members 70 with the end members will lock the top and bottom members against disengaging movement.

2. A display cabinet of the character described comprising end, top, bottom and intermediate members having locking devices, the locking devices of the end members being complementary to those of the top, bottom and intermediate members, said locking devices being engaged and disengaged by 75 movement of the top and bottom members relative to said end members, pilaster members, said end members and said pilaster members also having complementary locking devices engaged and disengaged by movement of said pilaster members relative to said end members, the movement of the pilaster members being at an angle to the movement of the top and bottom members, whereby engagement of the pilaster members 80 with the end members will lock the top, bottom and intermediate members against 85 disengaging movement.

3. A display cabinet of the character described comprising end members having 90 their edges provided with locking devices, top and bottom members having locking devices on their inner faces, the locking devices of the end members being complementary to those of the other members, said locking devices being engaged and disengaged by movement of the top and bottom members relative to said end members, pilaster members, said end members and said pilaster members also having complementary locking devices 100 engaged and disengaged by movement of said pilaster members relative to said end members, the movement of the pilaster members being at an angle to the movement of the top and bottom members, whereby engagement of the pilaster members with the end members will lock the top and bottom members against disengaging movement.

4. A display cabinet of the character described comprising end members having 115 their edges provided with locking devices, top and bottom members having locking devices on their inner faces, the locking devices of the end members being complementary to those of the other members, said locking devices being engaged and disengaged by movement of the top and bottom members relative to said end members, pilaster members, the forward edges of said end members and the inner faces of the pilaster members 120 being provided with complementary locking devices engaged and disengaged by movement of said pilaster members relative to said end members, the movement of the pilaster members being at an angle to the 125 130

movement of the top and bottom members, whereby engagement of the pilaster members with the end members will lock the top and bottom members against disengaging movement.

5. A display cabinet of the character described comprising a stack of superposed knock down units each comprising end, top and bottom members having locking devices, 10 the locking devices of the end members being complementary to those of the other members, said locking devices being engaged and disengaged by movement of the top and bottom members relative to said end members, 15 pilaster members, said pilaster members and all of the end members of a stack having complementary locking devices engaged and disengaged by movement of said pilaster members relative to said end members, the 20 movement of the pilaster members being at an angle to the movement of the top and bottom members, whereby engagement of the pilaster members with the end members will lock the top and bottom members 25 against disengaging movement, each pilaster member extending from the top to the bottom of the stack.

6. A display cabinet of the character described comprising knock down units arranged end for end, each unit comprising end, top and bottom members having locking devices, the locking devices of the end members being complementary to those of the other members, said locking devices being 30 engaged and disengaged by movement of the top and bottom members relative to said end members, pilaster members, said end members and said pilaster members also having complementary locking devices engaged and disengaged by movement of said 35 pilaster members relative to said end members, the movement of the pilaster members being at an angle to the movement of the top and bottom members, whereby engagement of the pilaster members with the end members will lock the top and bottom members against disengaging movement, the abutting ends of the units being engaged by a single pilaster.

50 7. A display cabinet of the character described comprising a plurality of superposed knock down units each comprising end members having their edges provided with locking devices, and top and bottom members having locking devices on their inner

faces, the locking devices of the end members being complementary to those of the other members, said locking devices being engaged and disengaged by movement of the top and bottom members relative to said end 60 members, pilaster members, the forward edges of all of the end members of the stack, and the inner faces of the pilaster members being provided with complementary locking devices engaged and disengaged by 65 movement of said pilaster members relative to said end members, the movement of the pilaster members being at an angle to the movement of the top and bottom members, whereby engagement of the pilaster members with the end members will lock the top and bottom members against disengaging movement, each pilaster member extending throughout the height of the stack.

8. A display cabinet of the character described comprising a plurality of stacks of knock down units having abutting ends, each unit comprising end members having their edges provided with locking devices, and top and bottom members having locking devices on their inner faces, the locking devices of the end members being complementary to those of the other members, said locking devices being engaged and disengaged by movement of the top and bottom members relative to said end members, pilaster members, the forward edges of all of the end members of each stack, and the inner faces of the pilaster members being provided with complementary locking devices 80 engaged and disengaged by movement of said pilaster members relative to said end members, the movement of the pilaster members being at an angle to the movement of the top and bottom members, whereby engagement of the pilaster members with the end members will lock the top and bottom members against disengaging movement, each pilaster member extending throughout the height of the stack, the abutting end 85 members of the units of adjacent stacks being engaged by the same pilaster member.

In testimony whereof I have hereunto set my hand in presence of two subscribing witnesses.

WILLIAM T. HORMES.
